CLAIM

The ornamental design for a candy bar mold, as shown and described.

DESCRIPTION

FIG. 1 is a perspective front view of a candy bar mold showing my new design;

FIG. 2 is a front view thereof;

FIG. 3 is a back view thereof;

FIG. 4 is a left side view thereof;

FIG. 5 is a right side view thereof;

FIG. 6 is a top view thereof; and,

FIG. 7 is a bottom view thereof.

(Continued)

The broken lines shown in the drawings are for the purpose of illustrating portions of the candy bar mold that form no part of the claimed design.
